METHOD AND MEANS FOR THE MANUFACTURE OF GRAPHITE MOLDS AND THE LIKE

Josef Heuberger, Stockholm, Sweden, assignor to
Aktiebolaget Hammarbylampan, Stockholm,
Sweden, a company of Sweden

Application June 26, 1942, Serial No. 448,695
In Sweden August 6, 1941

6 Claims. (Cl. 18—34)

For the manufacture of molds from graphite or other material, for instance for metal-ceramic purposes, it has been usual to use a pressing contrivance substantially consisting of a press plunger and a matrix, in which finely divided graphite powder and so forth, with or without adhesive or other admixtures is pressed, whereupon the molds are sintered. In the production of molds of a simple configuration, the pressing of the graphite may be effected solely by a rectilinear movement of the press plunger relatively to the matrix. On the other hand, where the production of molds for objects presenting at any point a helically extending surface, or part of such a surface, is brought into consideration, which is the case, for instance, with twist drills or certain milling-cutters, a method of this kind cannot be employed. Especially in the case of graphite, where the material is distinguished by a leaf-like structure, it is desirable that the pressure shall be the same all over in planes at right angles to the direction of compression.

The present invention relates to a method for the manufacture of molds from graphite or similar objects having a helically extending surface, or part of such a surface, the said manufacture being performed through compression of finely divided graphite or the like, with or without the addition of other substance, in a matrix by means of a press plunger. According to the invention the press plunger and/or the matrix, or some part thereof, simultaneously with a rectilinear movement are caused to perform a rotary movement relatively to each other through the action of the pressure resistance of the pressing material against a helical surface on the press plunger and/or the matrix. In order that the condition in regard to the uniform pressure in planes at right angles to the direction of compression shall be maintained it is understood that the rotary movement must not be uniform at a uniform compression of the graphite mass, inasmuch as the relationship between pressure and compression is not a linear one. By reason of the fact that the pressure resistance of the pressing mass itself brings about the rotary movement, the desired positive control of the rotary movement is obtained, which results in that all details of the press plunger and those of the matrix, such as helically extending grooves, are filled with the graphite mass at a uniform pressure, that is to say, without "shrinkages" or indications of ruptures occurring in the finished mold.

The invention also involves means for carrying

the method into effect. According to one feature of such means the press plunger and/or the matrix, which together form the press chamber, and which have one or more helical press surfaces or part of such surfaces, are mounted to rotate freely so that the press plunger and the matrix, in addition to the linear movement in the press stroke of the press plunger, also may perform a rotating relative movement.

10 According to a further feature of the means according the invention, comprising a matrix and/or a press plunger consisting of more parts, only those parts of the device are mounted to rotate freely, which carry helical press surfaces 15 or are actuated by such surfaces during the pressing operation.

In order to facilitate the mounting of the plunger and/or the matrix, it may be found suitable to cause one of the elements, for instance 20 the press plunger, to perform the rectilinear movement, while the other element, such as the matrix or some part thereof, is arranged to perform the rotary movement.

The accompanying drawing illustrates some 25 embodiment of an arrangement according to the invention by way of diagrammatic representation. Figure 1 shows the use of a rotary press plunger, and Figure 2 shows a rotary matrix. Figure 3 30 illustrates a cross section of a matrix having an internal threaded surface.

According to Figure 1, the press plunger 2, which is provided with spiral- (helical-) shaped surfaces 3, is rectilinearly movable in relation to the matrix 4, which is provided with a bottom piece 5. At the same time, the press plunger is also mounted to be freely rotatable, for instance by means of ball bearings 1. In the production of the mold, the graphite mass, admixed, if desired, with adhesive and other substances, is filled 35 into the matrix, whereupon the press plunger is pressed into this mass. Through the pressure of the graphite mass against the spiral-shaped surfaces the plunger is caused to rotate at the same time, so that it will be screwed into the mass, so to say, the pressure being thus maintained uniform. The pressing of the mold having been 40 finished, the press plunger may again be readily screwed out, but if desired, it may be left in the mold during the subsequent sintering operation.

45 In the embodiment according to Figure 2, the rotary movement has instead been allotted to the matrix, while the press plunger only performs the rectilinear movement. To this end, the matrix 4 with its bottom piece may be fixedly or removably arranged on a freely rotatable table 6. The

mounting may be effected with the aid of suitable thrustbearings, for instance by means of roller bearings 7, which are arranged between the table and a base plate 8. The base plate and the table may be associated by means of a pin 9 which is relieved of load by means of a thrustbearing 10. Dust shields 11, 12 may be provided for the bearings.

It is also possible to cause the matrix to perform the rectilinear movement, while the press plunger is freely rotatable. If the matrix or the press plunger is made from a plurality of mutually movable parts, only the member cooperating with the spiral-groove need be rotatable.

Figure 3 shows such a device adapted to shape from graphite or similar material a mold with an exterior helical surface. The matrix 13 has a recess 14 adapted to receive the graphite powder and this recess has an internal screw thread 15 corresponding to the helical surface to be produced. The plunger 2 is provided with an extension 16 producing a recess in the finished product to be molded. The matrix is freely rotatable for example by means of ball bearings 17 arranged at the bottom of the matrix. Under the action of the pressure of the graphite mass against the threaded surface 15 upon pressing the plunger 2 downwards the matrix 13 will be caused to rotate so that a uniform pressure is produced in the graphite compressed.

As many changes could be made in the above method and construction and many apparently widely different embodiments of the invention could be made without departing from the scope thereof, as defined by the following claims, it is intended that all matter contained in the above description shall be interpreted as illustrative and not in a limiting sense.

What I claim is:

1. In a method of producing graphite molds and similar objects having at least in part a helically extending surface, the steps of compressing finely divided graphite in a press comprising a matrix and a press plunger, one of said matrix and plunger having a helically extending surface and effecting, during the compressing operation, simultaneously a relative rectilinear and rotary movement between the press plunger and the matrix, said rotary movement being effected automatically by the action, during said rectilinear movement, of the pressure resistance of the pressing mass against the helically extending surface on said one of said matrix and plunger.

2. In a method of producing graphite molds and similar objects having at least in part a helically extending surface, the steps of compressing finely divided graphite in a press comprising a matrix and a press plunger having a helically extending surface, and effecting, during the compressing operation, simultaneously a rela-

tive rectilinear and rotary movement between the press plunger and the matrix, said rotary movement being effected automatically by the action, during the said rectilinear movement, of the pressure resistance of the pressing mass against the helically extending surface on the press plunger.

3. In a method of producing graphite molds and similar objects having at least in part a helically extending surface, the steps of compressing finely divided graphite in a press comprising a matrix having a helically extending surface and a press plunger, and effecting, during the compressing operation, simultaneously a relative rectilinear and rotary movement between the press plunger and the matrix, said rotary movement being effected automatically by the action, during the said rectilinear movement, of the pressure resistance of the pressing mass against the helically extending surface on the matrix.

4. Means for producing graphite molds and similar objects having at least in part a helically extending surface, by compression of finely divided graphite, comprising in combination a press plunger and a matrix, which together form a pressing compartment and which possess at least one helical pressing surface, said plunger and matrix being linearly movable toward each other for compressing said graphite, and journal means for mounting one of said press plunger and matrix for rotary movement relative to the other during said relative linear movement and compression.

5. Means for producing graphite molds and similar objects having at least in part a helically extending surface, by compression of finely divided graphite, comprising in combination a two-part press plunger and a matrix, which together form a pressing compartment and which possess at least one helical pressing surface, said press plunger and matrix being linearly movable toward each other for compressing said graphite, and journal means for mounting one part of said press plunger for rotary movement relative to the other part and relative to said matrix during said relative linear movement and compression.

6. Means for producing graphite molds and similar objects having at least in part a helically extending surface, by compression of finely divided graphite, comprising in combination a press plunger and a two-part matrix, which together form a pressing compartment and which possess at least one helical pressing surface, said press plunger and matrix being linearly movable toward each other for compressing said graphite, and journal means for mounting one part of said matrix for rotary movement relative to the other part and relative to said press plunger during said relative linear movement and compression.
